UNITED STATES PATENT OFFICE.

EUGÈNE SCHNEIDER, OF LE CREUZOT, FRANCE, ASSIGNOR TO SCHNEIDER & CIE., OF PARIS, FRANCE, A LIMITED JOINT-STOCK COMPANY OF FRANCE.

LIGHT-ARTILLERY GUN.

1,310,878.

Specification of Letters Patent. Patented July 22, 1919.

Application filed February 11, 1916. Serial No. 77,715.

To all whom it may concern:

Be it known that I, EUGÈNE SCHNEIDER, a citizen of the Republic of France, residing at Le Creuzot, France, have invented a new and useful Improvement in or Relating to Light-Artillery Guns, which is fully set forth in the following specification.

This invention has for its object to provide an improved piece of light artillery so 10 constructed as to be capable of being easily carried by troops in the assault, and of being readily moved and handled in the line trenches and in the communicating trenches.

One of the characteristic features of the 15 improved piece of artillery is that the gun barrel or its cradle has formed in one piece with it or suitably fixed to it a rear appendix by means of which it is pivoted through the medium of a universal joint, such as a ball 20 and socket joint, to an anchoring device, such as a platform or table provided with a spade; the elevation and training of the gun being effected by directly turning the gun barrel or its cradle about the said ball and 25 socket joint on the anchoring device.

The supporting of the forward part of the 30 gun barrel may be effected by various means, such as for instance extensible, telescopic or other supports, or by straight racks or curved racks having their geometrical center 35 in the ball and socket joint by which the gun barrel is connected to the anchoring device, the gun barrel being adapted to be locked in its various positions of elevation by means of catches or teeth.

According to the invention the forward 40 support consists preferably of a train of wheels, and the turning of the gun barrel about the ball and socket joint is effected by longitudinal and transverse displacements of the gun carriage axle relatively to the gun barrel, and of the gun barrel relatively to the said axle.

Various embodiments of the invention are 45 illustrated by way of example in the accompanying drawings in which:

Figures 1 to 6 show one embodiment.

Fig. 1 is a side elevation partly in section along the axis of the gun in firing position.

Fig. 2 is a corresponding plan.

Fig. 3 is a cross section on the line III—III of Fig. 1.

Fig. 4 is a side elevation of the gun in position for transport.

Fig. 5 is a section of a detail on the line 55 V—V of Fig. 1; and

Fig. 6 is a part side elevation showing the gun in position for firing at very low angles of elevation.

Figs. 7 and 8 are vertical cross sections 60 illustrating two modifications.

Figs. 9 and 10 are side elevations of another modification showing the gun in three different positions of elevation.

Figs. 11 and 12 are respectively a side elevation in partial section and a plan of a further modification of the invention.

In all these figures, A is the gun barrel which is provided according to the invention, as a continuation to the rear of its 70 breech, with an appendix B by means of which it is pivoted by a ball and socket joint C to a suitable anchoring device such as a spade platform D.

In the examples shown, the appendix B is 75 assumed to be carried by the gun barrel, but it may equally well be carried by the cradle in which the gun barrel is arranged to recoil in the usual manner and carry with it one of the elements of the recoil brake. 80 Although the appendix B is shown as being formed in one piece with the gun barrel, it may equally well be affixed to or assembled with the latter by means of any suitable locking devices that will allow of taking the 85 gun to pieces for transport of the parts separately.

In the example shown in Figs. 1 to 6, the ball and socket joint C is itself pivoted by means of a longitudinal pivot pin e in a 90 block b which forms the rear end of the appendix B. The ball and socket joint is further mounted on a transverse pivot pin d carried by the spade-platform D, this mounting comprising two truncated conical 95 recesses in the ball that allow a limited transverse movement of the ball on the pivot pin d. The ball is engaged with a slide block D¹ provided with a tail d¹ constructed as a nut, which can be moved along a long 100

screw D^2 , journaled in a bracket D^3 on the platform, by any suitable means such as a ratchet e on the screw and a lever E coacting therewith. The platform serves also as a support for a bar F .

It will be readily perceived that by turning the platform D with the ball and socket joint C through 180 degrees on the pivot pin c , and then moving it downwardly and forwardly, it can be brought into the position shown in Fig. 4, and locked in this position by means of a pin inserted in the lugs b^1 and d^2 which are provided respectively on the block b and the platform D . The bar F can then serve as a push bar for transport purposes.

The appendix B is preferably so constructed as to act as a charging guide or chute either directly by its shape or by means of a suitably shaped inner plate B^1 fixed to the sides of the appendix proper.

The forward support of the gun barrel consists in the examples shown in Figs. 1 to 10, of a train of wheels, that is to say, of a gun carriage axle G with two wheels H , H .

In the examples shown in Figs. 1 to 6, and in Figs. 7 and 8, the elevation of the gun barrel as a result of the turning of the ball and socket joint C in the anchoring device D , is effected by a longitudinal displacement of the forward support relatively to the gun barrel, while the training of the gun barrel is effected by sliding the latter along the axle. For this purpose the axle G is formed with a longitudinal groove g (Figs. 2 and 3), in which there is adapted to slide by means of a corresponding tenon a member such as a pinion I meshing with a corresponding rack a formed on the underside of the gun barrel or of its cradle (Figs. 1 to 6). A longitudinal displacement of the train of wheels for the purpose of elevating the gun is produced by rotating the axle G and the pinion I thereon by means of operating handwheels J which are fixed on the said axle. The pinion rolls over the rack, whereby the support can be brought into the desired position, for instance into the extreme position of greatest elevation indicated in dot and dash lines in Fig. 1. The gun barrel can then be fixed in the desired position, for instance by means of the device shown, consisting of a U-shaped clamping member K journaled with its arms on the axle G . These arms inclose the pinion I between them. Inner packing pieces on the said arms act as cheeks bearing against the surfaces of the gun barrel. The crosspiece of the clamping member is formed as a nut in which works a screw L carrying a clamping jaw L^1 on its end.

When it is desired to be able to elevate the gun barrel through very low angles the gun barrel is provided with a second rack a^1 .

By turning the clamping member upside down on the axle, the clamping member can be brought into the position shown in Fig. 6, and the gun barrel being then engaged in the clamping member as shown in the same figure, the elevation of the gun barrel can be produced by rolling the pinion I over the rack a^1 .

Coarse training is effected by simply pushing the gun barrel transversely along the axle G , the fine training being obtained by operating the ratchet mechanism $E-e$.

In the modification shown in Fig. 7 the gun barrel has two ribs a , a^1 , provided in substitution for the racks shown in Figs. 1 to 6; they form a rolling track for a roller I adapted to rotate on the axle, the gun being locked in the desired position of elevation by means of a clamping apparatus $K-L-L^1$ or any other suitable device.

In the modification shown in Fig. 8 the train of wheels comprises an axle G carrying a pinion I which can move over a single lower rack a , which axle is itself adjustable vertically with relation to the wheels H . The axle G is journaled at each end in bearing M which can slide in a guide N^1 formed on a hollow journal N on which the hub of the wheel can turn. The bearing M can be raised or lowered in its guide by means of a screw O working in the said guide. For transport the axis of the axle G is brought in line with the axes of the hollow journals N , and the keys m of the handwheels J are removed, so that then the journals can be mounted on the axle.

In the modification shown in Figs. 9 and 10 the forward support of the gun barrel consists also of a train of wheels $H-H-G$ carrying on its axle G a pinion I adapted to slide in a groove for the purpose of training the gun barrel. The elevation of the gun barrel is effected in this modification by rolling the pinion over a toothed arc P carried by a collar p which can be fixed in place on the gun barrel in two positions 180 degrees apart, as shown respectively in Figs. 9 and 10. Clamping apparatus similar to that shown in the preceding figures is provided for the purpose of fixing the gun barrel in any desired position of elevation.

In the modification shown in Figs. 11 and 12 the forward support of the gun barrel is constituted by two toothed arcs Q carried by a circular soleplate q which is adapted to turn in a forward anchoring bedplate R . In this modification the ball and socket joint C is movable in a slide block S working in an arc-shaped guide T mounted on the spade platform D . The gun barrel is trained by shifting the slide block S in its arc-shaped guide by means of a rack and pinion gear actuated by a lever and ratchet as shown.

The gun barrel is elevated by causing two pinions U to roll over the toothed arcs Q. These pinions U are carried by a shaft u journaled in a collar V carried by the gun 5 barrel.

As shown in Fig. 3, when the forward support consists of a train of wheels, its bulk may be reduced by shifting the said wheels along the axle, for transport purposes or for bringing the gun into firing 10 position in the trenches.

It is to be understood that the details of the gun, such as the breech mechanism, the firing mechanism, the sighting and aiming 15 devices, the constructional details of the spade, platform, etc., may be varied at will.

What I claim is:—

1. In a light artillery gun, the combination, with the gun barrel, of a rear appendix 20 fixed thereto, an anchoring device such as a spade platform, and a universal joint between said rear appendix and said anchoring device said joint members being pivoted to said appendix by means of a longitudinal 25 axle and journaled on a fixed transverse axle on said anchoring device and comprising a slide block capable of transverse movement on said anchoring device, whereby the gun barrel may be elevated and trained by 30 direct turning of the gun barrel on said universal joint relatively to said anchoring device through which latter the resultant forces generated by the firing will necessarily pass.

2. In a light artillery gun, the combination 35 with the gun barrel, of a rear appendix fixed thereto, an anchoring device such as a spade platform movable relatively to the appendix and provided with a bar which 40 may serve as a hand bar when the anchoring device is raised for transport, and a universal joint between said rear appendix and said anchoring device, whereby the gun barrel may be elevated and trained by direct 45 turning of the gun barrel on said universal joint relatively to said anchoring device through which latter the resultant forces generated by the firing will necessarily pass.

3. In a light artillery gun, the combination 50 with the gun barrel, of a rear appendix fixed thereto, an anchoring device such as a spade platform, a universal joint between said rear appendix and said anchoring device, whereby the gun barrel may be elevated and trained by direct turning of the gun barrel on said universal joint relatively 55 to said anchoring device through which latter the resultant forces generated by the firing will necessarily pass, a forward support 60 for the gun barrel consisting of a plurality of wheels with a common axle, manual operating means on said axle, a pinion or roller slidably mounted on said axle and engaging a rack or rolling track on the gun

barrel, and a clamping apparatus mounted 65 on said axle for fixing the gun barrel in any desired position of elevation.

4. In a light artillery gun, the combination with the gun barrel, of a rear appendix fixed thereto, an anchoring device such as 70 a spade platform, a universal joint between said rear appendix and said anchoring device, whereby the gun barrel may be elevated and trained by direct turning of the gun barrel on said universal joint relatively 75 to said anchoring device through which latter the resultant forces generated by the firing will necessarily pass, a forward support for the gun barrel consisting of a plurality of wheels with a common axle, manual 80 operating means on said axle, a pinion or roller slidably mounted on said axle and engaging a rack or rolling track on the gun barrel, and a clamping apparatus mounted on said axle for fixing the gun barrel in any 85 desired position of elevation, consisting of a U-shaped member constructed as a nut in which works a screw carrying a clamping jaw adapted to be pressed against the gun barrel. 90

5. In a light artillery gun, the combination with the gun barrel, of a rear appendix fixed thereto, an anchoring device such as a spade platform, a universal joint between 95 said rear appendix and said anchoring device, whereby the gun barrel may be elevated and trained by direct turning of the gun barrel on said universal joint relatively to said anchoring device through which latter the resultant forces generated by the 100 firing will necessarily pass, a forward support for the gun barrel consisting of a plurality of wheels with a common axle, manual operating means on said axle, a pinion or roller slidably mounted on said axle and 105 engaging a rack or rolling track on the gun barrel, and a clamping apparatus mounted on said axle for fixing the gun barrel in any desired position of elevation, said clamping member being journaled on 110 said axle so as to be capable of being turned upside down when it is desired to move the gun barrel through low angles of elevation.

6. In a light artillery gun, the combination with the gun barrel, of an anchoring 115 device, a universal joint therebetween, a forward support for the gun comprising a plurality of wheels and a common axle, and means for increasing and decreasing the elevation of said gun by movement of the 120 same on said universal joint.

7. In a light artillery gun, the combination with the gun barrel, of an anchoring device, a universal joint therebetween, a forward support for the gun comprising a 125 plurality of wheels and a common axle, and means for increasing and decreasing the elevation of said gun by movement of the

same on said universal joint, said means comprising coacting members carried by said gun and axle.

8. In a light artillery gun, the combination with the gun barrel, of an anchoring device, a universal joint therebetween, a forward support for the gun comprising a plurality of wheels and a common axle, and means for increasing and decreasing the 10 elevation of said gun comprising a pinion and rack, one of which is carried directly by said axle and the other of which is carried by said gun.

9. In a light artillery gun, the combination with the gun barrel, of an anchoring device, a universal joint therebetween, a forward support for the gun comprising a plurality of wheels and a common axle, and means for increasing and decreasing the 15 elevation of said gun comprising an axially slid able member carried by said axle and a coacting member carried by said gun.

10. In a light artillery gun, the combination with the gun barrel, of an anchoring 25 device, a universal joint therebetween, a forward support for the gun comprising a plurality of wheels and a common axle, means for increasing and decreasing the elevation of said gun comprising coacting members 30 carried by said gun and axle, and means for clamping said gun in its positions of adjustment.

11. In a light artillery gun, the combination with the gun barrel, of an anchoring 35 device, a universal joint therebetween; a forward support for the gun comprising a plurality of wheels and a common axle, and means for increasing and decreasing the elevation of said gun comprising coacting 40 members carried by said gun and axle, said last-named means being so constructed as to enable adjustment of said gun through positions either above or below said axle.

12. In a light artillery gun, the combination with the gun barrel, of an anchoring 45 device, a universal joint therebetween, a forward support for the gun comprising a plurality of wheels and a common axle, said wheels being adjustable on said axle, and means for increasing and decreasing the elevation 50 of said gun by movement of the same on said universal joint.

13. In a light artillery gun, the combination with the gun barrel, of an anchoring 55 device, a universal joint therebetween, a forward support for said gun, and means for increasing and decreasing the elevation of said gun by movement of the same on said universal joint, said means comprising a 60 pinion and rack carried by said support and gun.

14. In a light artillery gun, the combination with the gun barrel, of an anchoring device, a universal joint therebetween, a forward support for the gun comprising a plu- 65

rality of wheels and a common axle, means for increasing and decreasing the elevation of said gun, and means for clamping said gun in its positions of adjustment.

15. In a light artillery gun, the combination with the gun barrel, of an anchoring device, a universal joint therebetween, a forward support for said gun, and means for increasing and decreasing the elevation of said gun comprising coacting means carried by 70 said gun and support, said last-named means comprising a member invertible to enable adjustment of said gun through high or low angles.

16. In a light artillery gun, the combination with the gun barrel, of an anchoring device, a universal joint therebetween, a forward support for the gun comprising a plurality of wheels and a common axle, and means for increasing and decreasing the 80 elevation of said gun comprising coacting members carried by said gun and axle, said last-named means comprising an invertible member whereby said gun may be supported for adjustment through angles either 85 above or below said axle.

17. In a light artillery gun, the combination with the gun barrel, of an anchoring device, a universal joint therebetween, a forward support for said gun comprising an 95 axle, said gun barrel being slidably mounted on said axle, and means for increasing and decreasing the elevation of said gun.

18. In a light artillery gun, the combination with the gun barrel, of an anchoring 100 device, a universal joint between said gun barrel and anchoring device, and means to train said gun by movement of the members of said universal joint relatively to said anchoring device.

19. In a light artillery gun, the combination with the gun barrel, of an anchoring device, a universal joint between said gun barrel and anchoring device, and means to 110 train said gun by movement of said universal joint relatively to said anchoring device, said last-named means comprising intermeshing relatively movable members carried by said joint and anchoring device.

20. In a light artillery gun, the combination with the gun barrel, of an anchoring 115 device, a universal joint between said gun barrel and anchoring device, and a longitudinal axle connecting said joint to said gun barrel.

21. In a light artillery gun, the combination with the gun barrel, of an anchoring device, and a universal joint between said gun barrel and anchoring device, said joint members being connected to said gun barrel 125 by a longitudinal axle and to said anchoring device by a transverse journal permitting relative lateral movement of the gun.

22. In a light artillery gun, the combination with the gun barrel, of an anchoring 130

device, a universal joint between said gun barrel and anchoring device, said joint members being connected to said gun barrel by a longitudinal axle and to said anchoring device by a transverse journal permitting relative lateral movement of the gun, and means to train said gun by movement of said universal joint relatively to said anchoring device.

10 23. In a light artillery gun, the combination with the gun barrel, of an anchoring device, a universal joint between said gun barrel and anchoring device, and connections between said gun barrel and anchoring device whereby the latter may be moved to a position wherein it will serve as a draft member.

20 24. In a light artillery gun, the combination with the gun barrel, of an anchoring device, a universal joint therebetween, a forward support for said gun, means for varying the elevation of said gun comprising co-acting members carried by said support and gun, and means for training said gun comprising co-acting members carried by said anchoring device and said universal joint.

25 25. In a light artillery gun, the combination with the gun barrel, of an anchoring device, a universal joint therebetween, a forward support for said gun, means for varying the elevation of said gun comprising co-acting members carried by said support and gun, said last-named means being so constructed as to enable adjustment of said gun through high or low angles, and means for

training said gun comprising co-acting members carried by said anchoring device and said universal joint.

26. In a light artillery gun, the combination with the gun barrel, of an anchoring device, a universal joint therebetween, a forward support for said gun with respect to which said gun barrel is slid able, and means to move said universal joint with respect to said anchoring device. 40

27. In a light artillery gun, the combination with the gun barrel, of an anchoring device, and a universal joint between said gun barrel and said anchoring device, said joint members being connected to said anchoring device by a transverse journal permitting relative lateral movement of the gun. 50

28. In a light artillery gun, the combination with the gun barrel, of an anchoring device, a universal joint between said gun barrel and said anchoring device, said joint members being connected to said anchoring device by a transverse journal permitting relative lateral movement of the gun, and means to train said gun by movement of said universal joint relatively to said anchoring device. 55
